AUTOMATIC VICAT CONTROL OF MOLD EXTRACTION

Raymond J. Miller, Detroit, Mich.

Application September 14, 1945, Serial No. 616,183

8 Claims. (Cl. 22—193)

1

This invention relates to the testing of materials to determine when a substance has attained a predetermined set or degree of hardness, and more particularly to the development of an improved method of casting wherein a determination is made as to when a mold investment has attained a predetermined set or degree of hardness, and to means for automatically actuating an extractor to separate a casting investment from a pattern or mold when no binding forces are exerted between the mold and the pattern.

In certain of the casting arts a hydro-setting plastic substance such as gypsum, plaster of Paris, etc., possessing the characteristic of undergoing a chemical and physical reaction when mixed with water or other suitable liquid is applied to a pattern or to a mold to form an investment having a casting cavity conforming with the contour of the pattern or mold. Many factors influence the setting time of mold investments, such as variations in humidity, and different storage and handling conditions. Successive batches of mold investments vary somewhat in chemical content and introduce erratic changes in the setting time.

After a mold forming substance of this type is mixed with a suitable liquid, a chemical and physical reaction takes place, and after a substantially predetermined time interval for any particular batch, a crystalline structure will begin to form, and the propagation of the crystalline structure will progress throughout the mass of the casting investment. The mold investment undergoes a preliminary shrinkage or contraction cycle followed by an expansion cycle as the mold investment assumes a set, and in certain types of mold investments a later contraction cycle is encountered as a final set is attained.

I have found that a casting investment possesses sufficient strength that it can be separated from a pattern or mold after it has passed through its initial contraction cycle, and that there is a definite relation between the subsequent shrinkage and expansion cycles and the resistance of the mold investment to penetration. A mold investment can be most easily separated from a pattern or mold when it has returned to normal after completion of the contraction cycle and before the expansion cycle has progressed to a point to increase the volume of the mold investment. At that time there are no binding forces between the contacting surfaces of the investment and the pattern or mold.

By determining the resistance of a casting investment to penetration at the time it passes

2

through the no shrinkage or expansion point on the subsequent shrinkage and expansion cycles, I am able to establish a constant factor for any class of mold investment. I can therefore extract a casting investment from a pattern or mold when a predetermined degree of hardness or set has been attained with assurance that the mold investment will be at approximately its normal point of no shrinkage and expansion whereupon the investment may be separated from the pattern or mold easier than at any other time.

By checking the resistance to penetration of a test sample of the substance used to make any casting investment, I am able to determine the time the casting investment passes through its neutral point between its shrinkage and expansion phases.

An object of this invention is therefore to provide a testing device to determine when a substance has developed a predetermined degree of hardness or set.

Another object is to provide a mechanism for indicating when a predetermined point of shrinkage or expansion has been attained in a substance that passes through shrinkage or expansion phases as it hardens or solidifies.

A further object of the invention resides in the development of an improved method of determining when a casting investment should be separated from a pattern or mold to insure separation at a point when no binding forces are encountered, to minimize breakage.

Yet a further object of the invention resides in the provision of a device for successively checking the resistance of a casting investment to penetration to determine the time when the casting investment may be separated from a pattern or mold with least danger of encountering breakage.

Still another object of the invention is to provide a testing device to initiate operations of a mechanical mechanism to perform some operation on a substance upon the attainment of a predetermined degree of hardness or solidification of the substance.

Another object of the invention is to provide a method of and apparatus for separating a casting investment from a pattern or mold wherein extraction will be automatically effected at a predetermined time relative to the setting of the casting investment.

A further object of the invention is to provide apparatus controlled by the degree of hardness of the molding material for extracting the casting investment.

A further object of the invention is to provide apparatus for measuring the hardness of the molding material at predetermined intervals and at spaced points, and operative upon the development of a predetermined degree of hardness in the molding material to set in motion other automatic apparatus for separating a mold from a contour former or pattern.

Yet a further object of the invention is to provide a method and apparatus wherein a sample of a molding material is segregated and tested for its physical qualities, and the treatment of the mold is controlled by the physical qualities developed in the sample.

Another object of the invention is to provide an apparatus wherein a freshly mixed batch of a hydrosetting plastic casting investment such as gypsum is separated into two parts, one part being introduced into a flask to form a mold and the other part being segregated and continuously tested for change in hardness, the casting investment being extracted from a pattern or mold when the second part has been found to have a predetermined degree of hardness.

A further object of the invention is to provide apparatus of the type described, which shall be of improved design and easily manufactured and maintained in operation.

Other objects and advantages of this invention will be apparent from the following detailed description considered in connection with the accompanying drawings, submitted for purposes of illustration only, and not intended to define the scope of the invention, reference being had for that purpose to the subjoined claims.

In the drawings wherein similar reference characters refer to similar parts throughout the several views:

Fig. 1 is a side elevation, partly in section, of a device embodying the invention.

Fig. 2 is a sectional view taken substantially on the line 2—2 of Fig. 1, looking in the direction of the arrows.

Fig. 3 is a horizontal sectional view taken substantially on the line 3—3 of Fig. 4, looking in the direction of the arrows.

Fig. 4 is a vertical sectional view of the upper portion of the device shown in Fig. 1.

Fig. 5 is a diagram showing the relation between the testing apparatus and the mold extracting apparatus.

Fig. 6 is a graphical chart showing the variation in physical characteristics of a typical casting investment.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The testing apparatus shown in Figs. 1 to 4 comprises a base member 10 having a frame member 12 and a cover member 13, the three members being fitted together to constitute a housing for certain movable parts of the apparatus.

One or more vertical posts 15 extend between the base 10 and the frame member 12, to support the latter. In the lower portion of the housing is journaled a horizontal shaft 14 driven by a small electric motor 16, a reduction gear 18 of

suitable construction being interposed between the motor 16 and the shaft to cause the shaft to rotate a slow speed.

In order further to reduce the speed of the shaft 14, a cam 20 is mounted upon the shaft 14 and operates to intermittently open and close a microswitch 22 connected in the wiring of the motor in such a manner as to intermittently cut off the supply of electric current thereto and thus allow the motor to stop until an adjustable time relay again starts the motor. The time relay may be set to close the circuit to start the motor 16 at any desired time intervals as for example from five to fifteen seconds depending on the frequency it is desired to test the substance undergoing examination.

At the upper portion of the housing is provided a rotatable sleeve 24, sealed against the entry of foreign matter by means of a sealing gasket 26, held in place by a collar 27. Slidably mounted in the sleeve 24 for vertical movement is a shaft 28 having at its upper end a tray 30 within which is removably seated a container 32, of circular cross-section adapted to receive a quantity of material 33 to be tested, for example a hydrosetting plastic casting investment such as gypsum or plaster, etc.

A cam 34 is mounted on shaft 14 and contacts a spherical bearing 36 at the lower end of shaft 28, so that with each rotation of the cam the shaft 28 with its tray 30 and container 32 will be moved upwardly by a distance equal to the eccentricity or throw of the cam.

A pin 38 is fitted in the sleeve 24 and slides in a longitudinal groove 40 formed in the shaft 28, to cause the shaft 28 to rotate with the sleeve 24, while permitting longitudinal movement of the shaft 28 in the sleeve 24. The arrangement constitutes the equivalent of a splined connection.

The lower portion of sleeve 24 is formed with an integral pinion 42, below which extends an integral annular portion 44. A collar 46 is rotatably mounted on the portion 44 and is connected thereto by means of an overrunning clutch 48 which engages the outer surface of portion 44, so that as the collar 46 is rotated in the clockwise direction as viewed from above, the sleeve 24 and shaft 28 will rotate with it, but movement of the collar 46 in the opposite direction will not cause rotation of the sleeve or shaft.

Oscillating movement of the collar 46 is brought about by means of a cam 50 mounted on shaft 14, and adapted to engage the lower end of a rocking lever 52. The rocking lever 52 is pivoted intermediate its ends by means of a pin 54 to a vertically extending portion of the frame member 12, the upper end 56 of the lever 52 being formed as a ball and engaging in an aperture in a boss 58 formed on the collar 46.

The lower end of the lever 52 is formed of hooked shape as indicated at 59, to engage the cam 50 as shown in Fig. 2. It will be seen that upon each rotation of the shaft 14 the cam 50 will move the upper end 56 of the lever 52 to the left as seen in Fig. 2, causing rotation of the collar 46 in the clock-wise direction as viewed from above, and producing an interrupted rotation of the container 32 and its contents.

After the cam 50 has passed the end 59, the rocking lever will be returned, by spring means (not shown), to its original position, and upon further rotation of the shaft 14 the cycle just described will be repeated.

In order to permit the stroke of the end 56 of the lever 52 to be varied, additional holes 55 and

57 for the reception of pin 54 are provided in the housing 12 and in the rocking lever 52 respectively.

The housing 10, 12, 13 is formed in the hollow shape shown, so as to constitute a container for lubricant, which will be distributed by the cams 34 and 50 to other moving portions of the apparatus.

Upon a stud 60 secured to the upper portion of member 13 is rotatably mounted a gear 62, meshing with the pinion 42 and intermittently driven thereby. Formed integral with or fixedly secured to the gear 62 is an eccentric 64 which cooperates with a strap 66 to cause oscillation of a rod 68 and a pivot pin 70. The pin 70 is secured to a reciprocably base plate 72 having sloping side walls which engage, in slideable relation, a pair of horizontal ways 74, so that rotation of gear 62 will cause the plate 72 to reciprocate in the ways 74. The ways 74 are secured to the upper portion of member 13 by means of bolts 76, and one of the ways may be made adjustable by means of bolts 78 and shims 80.

The plate 72 is formed with an annular flange 82 which extends upwardly through an aperture 84 in the cover member 13 and supports a column 86. In order to prevent the entry of foreign matter through the aperture 84, a flexible sealing gasket 87 is secured by screws 88 to the flange 82 and to the member 13.

The column 86 carries a control head 90, which is adjustably mounted thereon. The head 90 may be formed in two sections, secured together by means of bolts 91. Carried by the head 90 in juxtaposition to the container 32 is a Vicat needle 92, designed to test the resistance to penetration of the material 33 in the container.

Needles 92 of different sizes may be selectively mounted in a cylindrical holder 94, provided at its upper end with a pin 96 whereby weights 98 may be placed upon the holder to add to the weight thereof and thereby increase the force urging the needle 92 downwardly. The holder 94 is mounted by means of upper and lower cross pieces 100 and 101 between two flexible ribbons 102 passing over pulleys 104 and 105 mounted on shafts 106 and 107 in the testing head 90. One end of the ribbons 102 are secured to the upper cross pieces 100 by means of pins, and the other ends of the ribbons pass through the lower cross pieces 101 which act as guides and are secured to one end of springs 103 having their upper ends secured to the upper cross pieces 100 as illustrated. The ribbons 102 thus resiliently engage the pulleys 104 and 105.

The shafts 106 and 107 are mounted in adjustable bearings 109, which if desired may be of jeweled or other low friction type to minimize resistance to rotation of the pulleys. Rotation of pulleys 104 in either direction is limited by means of a pin 110 mounted in a lateral wall of the testing head and extending into an arcuate slot 111 formed in one of the pulleys 104 as illustrated.

A magnet 112 is mounted on the ribbons 102 by means of a bracket 114 extending between the spaced ribbons 102 in such a manner that it may be adjusted vertically. The magnet 112 is so positioned that upon upward movement of the Vicat needle 92 the magnet will be moved downwardly past a sealed tube or capsule 116 removably mounted in spring clips 118 upon a bracket 120 fixed to the inner surface of the head 90.

The bracket 120 is made vertically adjustable by means of screws 122 seated in vertical slots

124, adjustment being brought about by means of a hand operated screw 126 threaded in a horizontal flange 128 of a second bracket positioned beneath the bracket 120. The upper end of the screw 126 engages a horizontal flange 130 formed on bracket 120, so that by loosening screws 122 and operating screw 126 the capsule 116 may be brought to the desired position.

Within the capsule 116 is mounted a swinging switch member 132, pivoted at 134 and formed with two depending arms. Upon one of the depending arms is mounted an armature 136, of ferro-magnetic material, so that when the magnet 112 moves to the level of the armature 136, the armature will be attracted to the magnet and will rotate the switch member 132 in the clockwise direction about its pivot 134 as viewed in Fig. 4.

The switch member 132 is formed with a second depending arm 138, of electrically conducting material adapted to move into and out of contact with a drop or mass 140 of mercury or other electrically conductive material. The arm 138 and mercury 140 constitute a switch to control a circuit 142, in the known manner, so that when the armature 136 is moved in the clockwise direction as above described the circuit will be closed.

As illustrated diagrammatically in Fig. 5, the circuit 142 controlled by movement of the Vicat needle 92 controls a relay switch 143 of a second circuit 144. The second circuit 144 communicates with a suitable source of current and is connected to energize a solenoid 145 to open a valve 146 when the solenoid is energized. The valve 146 is positioned in a conduit 148 interposed between a source 150 of fluid subjected to pressure and a cylinder 152 having a piston 154 slidably mounted therein.

Closing of the switch 138-140 by movement of the Vicat needle 92 will result in upward movement of the piston 154 in the cylinder 152 as illustrated in Fig. 5. The piston 154 is connected through a piston rod 155 and other mechanical means indicated diagrammatically at 156 to a flask 158 such as the cope portion of a mold in such manner that upward movement of the piston 154 will result in extraction of the cope mold 159 from a contoured member or pattern 161.

In addition to the adjustments above described, the entire head 90 may be adjusted vertically of the column 86. The head 90 is slideable on the column by virtue of a circular bearing member 162. The upper portion of the column 86 is formed with a vertical groove 164 to receive a rack 166 secured therein by means of screws 167.

A pinion 168 is journaled in the head 90 on a transverse shaft 170 and engages the rack 166 so that rotation of the pinion will move the head up or down along the column 86. One or more hand levers or cranks 172 are fixed to the shaft 170 to permit such rotation.

In order to facilitate the vertical adjustment of the head 90, a counterweight 174 is suspended at the end of the head 90 by means of a cable 176. The cable 176 passes over a pulley 178 mounted on the side of the head 90, and a second pulley 180 mounted in the upper end of the column 86 and the opposite end of the cable is attached to a bracket 182 fixed to the upper end of the head. In this way, the counterweight 174 substantially balances the weight of the head, so that adjustment of the latter is facilitated,

The diagram of Fig. 6 illustrates the progressive change of physical characteristics of a typical casting investment of the hydro-setting type such for example as gypsum, plaster of Paris, etc. after having been mixed with water or other suitable liquid. The curve marked A is the shrinkage and expansion curve while the curve marked B indicates the crushing strength of the mold investment in pounds per square inch, or its resistance to penetration.

The casting investment is preferably introduced into the liquid with which it is to be mixed at the point 190 on the chart, and is allowed to soak therein for any suitable predetermined interval of time depending on the type of mold investment employed, such for example as for one minute or to the point 192 on the chart. The casting investment is then mixed for a suitable predetermined interval of time depending on the materials employed, such for example as for one minute or from the point 192 to the point 194 on the chart.

After the mixing operation has been performed, the casting investment in the form of a slurry is introduced into the flask 160 having a pattern 161 therein. A sample batch of the mix is poured into the container 32 and is positioned on the tray 30 of the testing device. A setting or hardening action occurs after a substantially predetermined time interval depending on the type of casting investment employed due to a combined chemical and physical reaction that takes place after the mixing of the casting investment forming ingredients.

Certain types of casting investments pass through a creaming phase as illustrated between the points 194 and 196 on the chart, and thereafter a crystalline structure will begin to form and will propagate throughout the mix as the investment attains a set or hardens. The setting action is generally accompanied by an initial contraction or shrinkage as the mold forming investment begins to solidify or set such for example as from the point 196 to the point 198 on the chart due to a contraction of the slurry. Thereafter, the mold passes through an expansion cycle, returning to the normal after completion of the shrinkage cycle and before the expansion cycle has progressed to a point to increase the volume of the investment as illustrated at 200 on the chart, and continues to expand to a point such as 202 due to an expansion of the slurry as crystallization or solidification progresses throughout the mold forming investment.

The curve B indicates the progressive increase of the crushing strength of the investment or its resistance to penetration as it passes through its successive shrinkage and expansion cycles. The investment has no resistance against crushing until the point 203 is reached corresponding with the beginning of the formation of the crystalline structure as illustrated by the point 198 on the curve marked A. It thus appears that in the example illustrated, the mold has no appreciable resistance to crushing or penetration until approximately eight minutes after the investment is introduced into the liquid.

In the illustrated example the crushing strength or resistance to penetration increases substantially as a straight line function from the point 210 corresponding with the point 200 on the A scale indicating substantially no contraction or expansion. The casting investment possesses sufficient strength that it will hold together and can be extracted from a pattern or mold some-

what before it reaches its point of maximum shrinkage indicated by the point 198 on the A scale.

As pointed out above, it is desirable that the investment be extracted from the pattern or mold at substantially the no shrinkage and expansion point so that the minimum binding forces will be encountered between the casting investment and the pattern or mold. The test sample 33 in the container 32 exhibits the same physical characteristics as the casting investment introduced into the flask 160 because they are both taken from the same mix.

As indicated by the chart, there is a definite relation between the shrinkage and expansion cycles of the casting investment and its crushing strength or resistance to penetration. By suitably calibrating the Vicat needle 92 by removing or adding weights 98 on the holder 94, and using a Vicat needle 92 of appropriate size the testing device can be calibrated for any particular casting investment.

By checking samples of casting investments of various classes I have been able to determine a relation between the resistance to penetration and the shrinkage and expansion cycles of each class of investment. With this information known, the control testing device is so calibrated that the Vicat needle 92 will be moved upwardly by the increasing resistance to penetration when the setting or hardening of the test sample 33 has progressed to the desired point on the successive shrinkage and expansion cycles illustrated on the curve A of Fig. 6.

Operation of the testing device is started by actuating a switch controlling the motor 16 whereupon the shaft 14 is rotated at slow speed. Rotation of the shaft 14 is operable through the cam 34 to elevate the shaft 28 to project the Vicat needle 92 into the test sample 33.

As illustrated in Fig. 2 the cam 34 operates to elevate the shaft 28 and container 32 during approximately one-half of the revolution of the shaft 14. When the shaft 28 and container 32 are in the lowered position with the Vicat needle 52 out of the test sample 33, the cam 50 engages the hooked end 58 of the lever 52 to move it angularly about the pin 54. When the lever 52 is thus actuated its upper end 56 oscillates the boss 58 and collar 46 in the clock-wise direction as viewed from above Fig. 1 whereupon the one-way clutch 48 rotates the sleeve 24 in the housing. The shaft 28 operably connected to the sleeve 24 by the pin 38 sliding in groove 40 will be rotated with the sleeve 24 to index the container 32. It thus appears that as the shaft 14 is rotated through one complete revolution to elevate the shaft 28, the container 32 will be indexed so that the Vicat needle 92 will be projected into a different portion of the test sample 33.

Progressive oscillation of the sleeve 24, by actuation of the lever 52 and collar 46, is effective through the gear 42 to rotate the gear 62 carried by the stud 60 secured in the cover plate 13 of the housing. Rotation of the gear 62 is effective through cam 64, strap 66 and link 68 and pin 70 to reciprocate the base plate 72 in the ways 74 to move the head 90 toward and away from the shaft 28 to project the needle 92 into a fresh portion of the test sample 33 after the container 32 has been rotated a complete revolution.

It will be apparent that the needle 92 is moved back and forth from a point adjacent the outer

edge of the container 32 toward the center, and that the container 32 is progressively rotated each time it is elevated to project the needle 92 into the test sample 33 so that the needle is projected into a fresh portion of the test sample at each penetration.

As the test sample 33 progressively solidifies, or assumes a set, the resistance of the material 33 to penetration of the needle 92 progressively increases as indicated by the scale B of Fig. 6. When the resistance to penetration reaches a point that the needle 92 will not project into the test specimen 33, the Vicat needle 92 and the holder 94 will be elevated whereupon the flexible ribbons 102 rotate the pulleys 104 and 105 in the clock-wise direction as viewed in Fig. 4.

When the test specimen 33 attains a sufficient set that the Vicat needle is elevated to such a point that the magnet 113 carried by the ribbons 102 is moved downwardly in alignment with the armature 136 of the sealed capsule or tube 116, the armature 136 is attracted by the magnet 113 whereupon the switch member 132 is oscillated about its pivot 134 to move the arm 138 to contact the drop of mercury or other electrically conductive material 140 to close the circuit through the leads 142.

Closing of the circuit 142 is operable through the relay switch 143 to complete a circuit through the leads 144 to energize the solenoid 145 to open the valve 146 positioned in the conduit 148. Opening of the valve 146 in the passage 148 directs fluid under pressure from the source of fluid pressure 150 to the cylinder 152 to elevate the piston 154. Elevation of the piston 154 is operable through the piston rod 155 and mechanism 156 to extract the mold 159 from the pattern 161.

The actuating mechanism is calibrated in such a manner that extraction of the casting investment from the pattern or mold will occur at substantially the point of no shrinkage or expansion indicated by the point 200 on scale A of the chart Fig. 6 because at that time no binding forces will be encountered between the casting investment and the surfaces of the pattern or mold.

By checking the successive shrinkage and expansion cycles of a particular casting investment, the point of maximum shrinkage 188 and the point of no shrinkage and expansion 200 on the expansion cycle, and the point 202 of maximum expansion can readily be determined. By calibrating the testing device in such a manner that the magnet 112 actuates the switch 132 by attracting the armature 136, and suitably calibrating the relay 143 it is possible to assure actuation of the mold extracting mechanism at the precise time that the mold investment is passing through its no shrinkage and expansion point on the curve illustrated in Fig. 6. Minimum mold breakage will thus be encountered, and molds can successively be extracted with assurance that they will be subjected to minimum binding forces.

While this invention has been described with particular reference to casting investments it will be apparent that it is equally applicable to the testing of any substance that undergoes a change whereby the resistance of the substance to penetration is increased or decreased. It will also be apparent that mechanism capable of performing any desired operation or sequence of operations can be set in motion and actuated automatically depending on the increase in hardness or solidification of the substance being tested. If desired the device can be calibrated to set any

mechanism in motion upon the attainment of any desired degree of shrinkage or expansion by calibrating the device to actuate a switch upon the attainment of predetermined resistance to penetration.

Features disclosed but not claimed herein are being claimed in my copending application Serial No. 157,966, filed April 25, 1950.

I claim:

1. The method of forming a mold and extracting it from a pattern which comprises forming an investment mix embodying substantially predetermined proportions of a batch of plaster of Paris and water having the characteristics of undergoing an initial contraction followed by a subsequent expansion and an increasing resistance to penetration as it hardens, testing this mix to determine its resistance to penetration at its point of no expansion and contraction, forming a mold of an investment mix embodying substantially the same predetermined proportions of water and plaster of Paris from said batch, and separating the mold from the pattern when a resistance to penetration is encountered in said mold mix corresponding with the resistance to penetration at the point of no expansion and contraction of said first mentioned mix.

2. The method of forming a mold and extracting it from a pattern and flask which comprises forming an investment mix embodying substantially predetermined proportions of a batch of plaster of Paris and water, testing this mix to determine its hardness at its point of no expansion and contraction, forming a mold of a second mix formed of substantially the same predetermined proportions of water and plaster of Paris from said batch, and separating the mold from the pattern and flask when its hardness progresses to a point substantially the same as the hardness of the first mentioned mix at its point of no expansion and contraction.

3. The method of forming a plaster of Paris mold and extracting it from a pattern which comprises forming an investment mix of plaster of Paris of a class having the characteristics of undergoing an initial contraction followed by a subsequent expansion and as it hardens, testing the mix to determine its hardness at its point of no expansion and contraction, forming a mold of plaster of Paris of said class, and separating the mold from the pattern when its hardness approximates the hardness of plaster of Paris of said class at its point of no expansion and contraction.

4. The method of forming a mold of a hydro-setting plastic casting investment such as gypsum possessing the characteristic of attaining a set and extracting the mold from a pattern which comprises forming an investment mix embodying substantially predetermined proportions of a batch of gypsum and water, testing this mix to determine its degree of set at its point of no expansion and contraction, forming a mold of a second mix formed of substantially the same predetermined proportions of water and gypsum from said batch, and separating the mold from the pattern when its degree of set progresses to a point substantially the same as the degree of set of the first mentioned mix at its point of no expansion and contraction.

5. The method of forming a mold and extracting it from a pattern which comprises forming an investment mix embodying substantially predetermined proportions of a batch of plaster of Paris and water having the characteristics of un-

dergoing an initial contraction followed by a subsequent expansion as its setting progresses, testing this mix to determine its degree of setting at its point of no expansion and contraction, forming a mold of a second mix formed of substantially the same predetermined proportions of water and plaster of Paris from said batch, and separating the mold from the pattern when its degree of setting approximates the degree of setting of said first mentioned mix at the point of no expansion and contraction.

6. The method of forming a mold and extracting it from a pattern which comprises forming an investment mix embodying substantially predetermined proportions of a batch of plaster of Paris and water having the characteristics of undergoing an initial contraction followed by a subsequent expansion and an increasing resistance to penetration as it attains a set, testing this mix to determine its resistance to penetration at its point of no expansion and contraction, forming a mold and a test specimen of a second mix formed of substantially the same predetermined proportions of water and plaster of Paris from said batch, and separating the mold from the pattern when a resistance to penetration is encountered in the test specimen substantially corresponding with the resistance to penetration of said first mentioned mix at its point of no expansion and contraction.

7. The method of forming a mold and extracting it from a pattern which comprises forming an investment mix embodying substantially predetermined proportions of a batch of plaster of Paris and water, testing this mix to determine its degree of set at its point of no expansion and contraction, forming a mold and a test specimen of a second mix formed of substantially the same predetermined proportions of water and plaster of Paris from said batch, and separating the mold from the pattern when the degree of set of the test specimen progresses to a point substantially

the same as the degree of set of the first mentioned mix at its point of no expansion and contraction.

8. The method of forming a mold and extracting it from a pattern which comprises forming an investment mix embodying substantially predetermined proportions of a batch of plaster of Paris and water, testing this mix to determine its hardness at its point of no expansion and contraction, forming a mold and a test specimen of a second mix formed of substantially the same predetermined proportions of water and plaster of Paris from said batch, and separating the mold from the pattern when the hardness of the test specimen progresses to a point substantially the same as the hardness of the first mentioned mix at its point of no expansion and contraction.
